UNITED STATES PATENT OFFICE

EDGAR F. HATHAWAY, OF WELLESLEY, MASSACHUSETTS, ASSIGNOR TO SHAWMUT ENGINEERING COMPANY, OF DORCHESTER, MASSACHUSETTS, A CORPORATION OF MASSACHUSETTS

YARN CARRIER OR TUBE FRAME

Application filed May 1, 1929. Serial No. 359,648.

My present invention deals with the handling of sets of threads or yarns, especially tuft yarns for moquette or other pile fabric looms such as Axminster carpet looms, 5 and more particularly aims to provide improved means for holding and presenting such threads or yarns in preparation for and during the weaving operation. This application is a division of my co-pending application Serial No. 317,728, filed November 7, 1928, the latter in turn being a continuation in part of my application Serial No. 290,916, filed July 7, 1928.

In the drawings illustrating by way of example one embodiment of my present invention.

Fig. 1 is a plan of a portion of a tuft-yarn carrier or tube-frame in accordance with the invention;

20 Fig. 2 is a vertical cross-section through the same; and

Fig. 3 is a bottom perspective view of a portion of an attaching strip.

In the illustrative embodiment of the invention, the tuft-yarn carrier or tube-frame comprises a frame or main longitudinal supporting element 1, shown as a tubular metallic member or bar but which may be of other material or otherwise formed, for instance, 25 as a wooden bar. The length of this frame or carrier proper is such that it may support along it one or more tuft-yarn spools of customary length. Each such spool is rotatably supported upon the frame and the latter is 30 adapted for connection with the carrier chain of a loom, in any desired or usual manner, for example, as illustrated and described in my applications above mentioned.

The ends of the series of yarns or yarn 40 units depend from the supported spool or spools across one face of the frame 1, that at the left as viewed in Fig. 2. For the purposes of the present application that side or face of the frame across which the yarn 45 ends extend is referred to as the frame front, while the face or portion of the frame at an angle thereto and below it is termed the under portion or bottom of the frame.

Along one face of the frame, the bottom 50 face as herein illustrated, I provide means

for spacing the yarns and for guiding the yarn-engaging devices or grippers of the loom. This means as shown comprises a longitudinal series of wall-forming barriers, 55 guide members or guides 9'. These guides are preferably metallic strip-like devices or bars distributed along the frame in edgewise relation thereto, each having one end extending outwardly or laterally beyond the bottom face of the frame and at the side across which 60 the yarn ends extend.

The barriers or guides 9' are removably secured in their relation substantially as illustrated as by means of an attaching strip 10 having apertures 11, see Fig. 3, at suitable 65 intervals for receiving fastening means such as screws or bolts 12, Fig. 2, which extend through corresponding openings in the adjacent face, herein the bottom face, of the frame 1 and removably engage the opposite 70 frame wall through the medium of lock nuts 13 or the like. The edge of each such opening 11 in the attaching strip preferably is up-set as indicated at 14, Fig. 2, to facilitate 75 and insure accurate positioning of the attaching strip relative to the frame.

The attaching strip 10 as illustrated comprises a flange 15 depending along one side portion of the strip. This flange, together with the adjoining portion of the strip if desired, is provided with a series of formations such as slots, notches, perforations or the like 80 16, each adapted to receive the adjacent portion, herein the inner end portion, of one barrier or guide 9' of the series. The inner end 85 portions of said barriers are adapted to be received in these formations, preferably with a slightly loose fit, each having at their extremity a tongue 17 for reception in the appropriate formation 16 of the attaching strip. 90

Additional means for positioning and retaining the yarn-spacing and gripper-guiding members or guides 9' preferably is provided, desirably along a portion of the attaching strip 10 spaced forwardly or toward 95 the right in Fig. 2 from the depending flange 15. As herein illustrated said means comprises a hollow or approximately U-shaped rib 18 bent or struck up from the body or strip preferably rounded substantially in the 100

manner shown and of a distinctly less height or depth than the corresponding dimension of the guides 9' to be received. This rib 18 has a series of slots, notches or the like 19, respectively in registry with the formations 16 of the depending flange previously mentioned, and of a width each to receive one guide 9', also desirably with a slightly loose fit. The rib 18, in the form illustrated and described, thus comprises in effect a series of straps or eyes aligned lengthwise of the attaching strip and of the carrier bar, and adapted to have passed through and beneath them a locking pin or bar 20, the latter passing through a locking formation or aperture provided for the purpose in each of the guides 9', thus holding or locking the latter removably in assembled position.

The outer or projecting end portions of the several barriers or guides 9' are formed as substantially straight noses 30 of a somewhat reduced vertical dimension as compared with the main portion of each. Cooperating with these portions of the several barriers or guides I have provided means for retaining the respective yarn units in proper spaced relation, one between each two adjacent guides, this means being constructed and arranged to permit broadside threading or positioning of the yarns in said relation when desired. This yarn retaining means may be formed as a part of the attaching strip 10 or as a separate longitudinal element or plate 31 positioned flatwise against the adjacent portion, herein the under face, of the frame 1, intermediate the latter and the attaching means 10, being provided with like-spaced apertures as the attaching strip 10 for the passage of the securing means 12. This plate 31 projects laterally at the front face of the frame and in proximity to the projecting portions of the several barriers 9'. At its outer or projecting portion it is stamped, sheared or otherwise formed to provide a series of front-entrance passages 32 into which the yarns may be threaded in a broadwise manner and wherein they will be positively retained by deflected portions, teeth or barbs 33. As clearly seen in Fig. 1, these off-set portions or barbs extend across and completely close in the spaces intermediate the respective guides 9', thus providing substantially continuous walled or inclosed guide passages from which the yarns may not escape in a broadwise manner unless they are intentionally bent or deflected about the respective barbs. They may, however, readily be entered into said guide spaces in a broadwise fashion as previously described.

It will be understood that my invention is not limited to the particular illustrative means shown and described, its scope being set forth in the appended claims:

1. In a yarn carrier or tube-frame, in combination with a main frame or carrier bar,

a longitudinal series of barriers or guides extending in substantial parallelism transversely of the frame at the lower portion thereof, each with one end projecting at the front of the frame, a yarn-spacing strip along the frame, having one side portion overlying the projecting ends of the barriers and formed with a corresponding series of broadside-threadable yarn passages, one between each two adjacent barriers, and with a deflected or barb-like portion for each such passage to prevent reverse escape of the yarns, and attaching means comprising two series of formations along the frame for individually receiving and positioning the respective barriers, the formations of the series nearer the frame front being of less vertical extent than the barriers.

2. In a tuft-yarn carrier or tube-frame for looms, a frame, a series of transversely extending guides adapted to receive yarns between them and to guide grippers of a loom in engaging the yarns, a yarn-spacing strip having a series of yarn-separating apertures each in communication with the outer edge of the strip for broadside entrance of the yarns and having a like series of barb-like means cooperating with said guides to close said apertures against reverse escape of the yarns, and means at the lower portion of the frame for positioning and attaching the guides thereto, including a multiplicity of projections in spacing relation with said guides at substantially their midlength portions and of less downward extent than the guides.

3. In a tuft-yarn carrier or tube-frame for looms, a frame, a series of transverse barriers or guide adapted to receive yarns between them, a cooperating yarn-spacing and retaining strip having along one side portion a series of broadside-threadable yarn-retaining members, and projecting means along the frame for attaching said barriers, the latter extending below the frame at their forward portions to constitute guides for the yarn-grippers of a loom, said barrier attaching means positioned wholly above and rearwardly of the gripper paths.

4. In a tuft-yarn carrier or tube frame for looms, a frame, a series of transversely extending guides adapted to receive yarns between them and to guide grippers of a loom in engaging the yarns, a yarn-spacer comprising a strip having along one side portion a series of broadside-threadable yarn-retaining members, said spacer so positioned on the frame as to bring one such member at each inter-guide space, and means for securing said guides to the frame, comprising a longitudinal strip having a flange, a series of guide-receiving formations along said flange, and a second and registering series of guide-engaging formations, of less height than the

guides, and spaced from said flange toward the frame front.

5. In a tuft-yarn carrier or tube-frame for looms, a frame, a series of transversely extending guides adapted to receive yarns between them and to guide grippers of a loom in engaging the yarns, a yarn-spacer comprising a strip having along one side portion a series of broadside-threadable yarn-retaining members, said spacer so positioned on the frame as to bring one such member at each inter-guide space, and guide-securing means adapted for attachment to the frame, comprising a strip having a flange, a series of notches, slots or like guide-receiving formations along said flange, and a hollow rib projecting from said strip, having a correspondingly spaced series of guide-engaging formations, and adapted to receive a pin for interlocking the guides with the strip.

6. In a yarn carrier or tube-frame for looms, a main frame, transversely extending barriers on the frame constituting yarn and gripper guides, a yarn spacer strip secured to the frame, having a plurality of broadside threadable yarn-guiding apertures, one for each inter-barrier space, and having barb-like portions, one for each yarn-guiding aperture and cooperating respectively with the adjacent barriers to retain the yarns against reverse broadwise escape, and an attaching member including a rear flange formed to receive and hold the rear portions of said barriers and a series of downward projections lying respectively between the several barriers intermediate the ends of the latter.

In testimony whereof, I have signed my name to this specification.

EDGAR F. HATHAWAY.
